Patent No. 3,164,406, dated Jan. 5, 1965. Divided
and this application Jan. 4, 1965, Ser. No. 422,988
10 Claims. (Cl. 214—317)

This application is a division of application Serial No. 10 54,541 filed Sept. 7, 1960, now Patent No. 3,164,406.

This invention relates to a container transfer device especially suited for mounting on a vehicle for transferring containers to and from the vehicle horizontally.

It is an object to provide a simple and dependable transfer device which can automatically engage and disengage the load and which is easy to align with the load without manually guiding or hooking hooks.

This invention comprehends a crane or derrick having a telescoping and lifting jib for mounting on a vehicle for transfer of containers to and from the vehicle, the jib being operable to extend from within the vehicle area horizontally out and down to engage the load and up and in to transfer the load onto the vehicle and vice versa to unload the vehicle. By providing the jib with these movements and having the engaging means directly mounted or integral on the jib extension or carrier (instead of providing a hoist on the jib, as is usual practice) the load can be easily aligned automatically and swinging and sway substantially reduced or eliminated.

It is a further object to provide a double jib for engaging opposite sides or ends of the container for greater rigidity in handling containers and a carrier for riding the jibs and telescoping thereon to extend beyond the mounting section of the jibs. It is a further object that the double jib straddle the container to reduce the overall height, and further to extend to place a plurality of containers on the vehicle. Other features such as using the jib to tilt the container to empty it are also provided for.

Still other or further objects will be pointed out hereinafter or should be apparent from consideration of this invention as described with reference to the accompanying drawings wherein:

FIGURE 1 is a perspective view of a truck mounted container loader about to pick up a container.

FIGURE 2 is a side elevation of the rear portion of the loader with a portion cut away to show the interior of the dashpot and shown dumping a load.

FIGURE 3 is a partial perspective and schematic view of the controls for the loader.

FIGURE 4 is a plan view of the loader.

Referring to the drawings, a truck mounted derrick 240, FIGURES 1—4 can be provided to engage and disengage containers 242 automatically and lift on or set off one or more of them on the truck with my hooks 10c.

Container 242 is preferably of the now common type having two trunnions 243 on opposite ends near the top. Hooks 10c each have a lower cam 18 to latch over the trunnions when let down thereon. The lower cams of the hooks are preferably bent out at the bottom to engage the container better. The hooks are mounted to swing on or with shaft 244 secured between parallel outward channels 246 which are spaced apart and connected by a channel section 248 to form a carrier 250. The hooks swing to vertical position by gravity and have an upper cam 30 which engages the trunnion to swing the hook wide open when the load is set down and the derrick is lowered further. A dashpot 32 delays the closing of both hooks if they are secured to turn with

shaft 244, but it is preferred to have the hooks turn on the shaft to latch independently of each other, and accordingly each hook has a dashpot 32 or its equal to delay the closing of hooks only after opening wide until the derrick can lift the hooks above the load. The dashpot is clevis mounted between the hook and carrier 250 as shown in FIGURE 2 and is further described in my Patent Number 3,164,406, issued January 5, 1965.

Carrier 250 is supported on a boom 252, which comprises two parallel channels 254 spaced to straddle container 242 and pivotally secured on the same axis facing out, one on each side and near the top of an A-frame 256, which is secured on the truck bed 258 near the front. Bar 260 at the rear above channels 254 spaces them. 15 Wheels or rollers 262 are spaced and secured along the facing faces of channels 254 to run in channels 246 and support the carrier. A cylinder 264 is clevis mounted to a yoke 266 connecting channels 254 on the under side thereof near A-frame 256. Yoke 266 is bent up in the center to permit use of a longer cylinder 264 without cutting away the truck bed to increase the lift of the derrick. Yoke 266 is therefore pivotally secured below each channel 254.

20 A cable 268 is anchored to the forward end of carrier 250 at 270 and is run back around pulley 272 on the extended end of the channel 254 on the same side of the truck. The cable runs from there over a pulley 274 on the pivot end of the boom and down around a drum 276. 25 Another cable 268' or a continuation of the first is run forward from the anchor 270 over a pulley 276 on the same pin as pulley 274 and down around drum 276 in the opposite direction so that the drum reels on and off opposite ends of the cable as it turns and runs the carrier in or out on the boom according to the direction of rotation of drum 276. Drum 276 can be turned and held by a hand winch or preferably by motor 280 through worm reducer 282 whose worm gear is secured on shaft 284 for turning drum 276. Motor 280 is preferably operated from the truck battery 286 by connection across the battery through reverse switch 288, shown in FIGURE 1. A similar cable arrangement is preferably provided on the opposite side of the truck and driven from the same shaft to reduce the possibility of the carrier twisting and to take part of the load. Boom 250 preferably extends to the edge of the truck frame or bed and carrier 250 extends out beyond the end of the boom as shown in FIGURES 1, 2, and 4, to pick up, set down and dump containers 242. Carrier 250 is therefore considered to be the telescoping end of the double boom 252.

50 Container 242 has runners 290 secured on the bottom to engage a rim 292 across the rear of the truck bed for dumping the box as shown in FIGURE 2.

Having thus described one of the many possible embodiments and applications of this invention, it should be understood that all matter contained in the above description or shown in the accompanying drawings shall be interpreted as illustrative and not in a limiting sense, further I contemplate to cover by the appended claims all variations and parts which fall within the true spirit and scope of this invention.

I claim as my invention:

1. A derrick for truck mounting for transferring containers to and from the truck and comprising in combination, a wide frame mast, a double boom pivotally mounted to the mast for straddling a container, a carrier for riding the boom, hook means pivotally secured on said carrier for latching onto a container when the boom is lowered thereto in alignment with the container, means actuated by the setting down of the container for opening said hook means when the hook means is lowered below latching position, and means for delaying the clos-

ing of the hook until it can be lifted above the container, means for raising and lowering the boom, and means for running the carrier back and forth on the boom to load and unload the truck.

2. A derrick as in claim 1, said carrier telescoping between a position within the boom and a position beyond the end of said boom.

3. A derrick as in claim 1, truck mounted, said mast being toward the front of the truck, said boom extending to substantially the rear of the truck, said carrier being extendible from the end of the boom opposite said mast to pick up and deposit containers behind the truck.

4. A derrick as in claim 3 and a dumping container therefore, trunnions on said container for engaging said hook means for lifting and tilting, dump flange means on the edge of the rear of the truck, said container having bottom means for engaging said flange means to tilt said container to empty when said bottom means is engaged on said flange means and said boom is lowered with said container over the edge of the truck.

5. A load transfer comprising, two parallel guides spaced apart to straddle the load, a frame, one end of each of said guides being pivotally secured to said frame to swing vertically together, telescoping carrier means supported on said guides to ride therealong and extending beyond the end thereof opposite said frame for transfer of the load, means for lifting and lowering the extended ends of said guides together, means secured to said carrier means for automatically engaging and disengaging the load, and means for extending and retracting said carrier means.

6. A device for transferring containers to and from a vehicle comprising in combination, two parallel telescoping booms spaced apart to straddle a container, mast means for pivotally supporting one end of the booms to swing together in parallel vertical planes, means connecting the opposite ends of the booms together to telescope together and hook means on the outer end of each boom for automatically engaging and disengaging a container therebetween, means for lifting and lowering the hook ends of the booms together and anti-friction rollers for relieving the friction in the telescoping booms, said booms being capable of bearing the full load in horizontal position.

7. A container transfer comprising in combination; boom means for mounting on a vehicle to swing vertically through a horizontal plane even when loaded, a carrier for riding said boom means, cable means for pulling said carrier back and forth on said boom means, means on said carrier for automatically engaging and releasing a container, said carrier being of shorter length than said

boom means and being designed to ride partly out of the end of the boom means and to travel substantially the length of the boom means to position said means for engaging the container clear of the vehicle and to be pulled back in with the load to position the load along the boom as viewed lengthwise of the boom means.

5 8. A transfer as in claim 7, a vehicle bed on which said boom means is mounted, said carrier having a travel on said boom means for placing a plurality of containers on said bed.

10 9. A vehicle mounting derrick for transferring loads to and from the vehicle and comprising in combination, a wide frame mast, a boom having parallel members spaced apart to straddle a load area on the vehicle and pivotally secured at one end to said mast at substantial height above the load bed of the vehicle to swing vertically through horizontal position, a load carrier for riding on said boom, friction relieving wheels between said boom and carrier supporting said carrier to ride substantially parallel the boom and to extend out a ways therefrom, rope and operating means for moving said carrier along said boom and for extending said carrier out a ways beyond the lifting end of the boom to transfer loads to and from the vehicle, and load engaging 15 means pivotally secured on and depending from the extending end of said carrier for engaging, suspending, and releasing the load, and means for lifting and lowering the boom for setting down and picking up the load beyond the edge of the vehicle.

20 10. A derrick as in claim 9, each load being a container having trunnions near the top, said load engaging means being hooks pivotally connected to said carrier to swing parallel the boom, straddle the container, and engage said trunnions when the vehicle is aligned with the 25 container for transfer and the boom is lowered.
